UNITED STATES PATENT OFFICE

EARL F. JAGER, OF CHICAGO, ILLINOIS

DOOR OPERATING AND LOCKING DEVICE

Application filed November 16, 1927. Serial No. 233,540.

This invention relates to devices for opening, closing and fastening sliding doors, and while capable of general use, is illustrated herein as applied to the door of a box car.

5 One of the purposes of this invention is to provide a device of the character indicated which will be strong and durable, economical to manufacture, easy to apply, which cannot be broken, removed or tampered with and 10 which consequently will be burglar proof.

Another purpose is to provide a device which will provide considerable leverage, thereby enabling the operator to force the door into a closed position, and also to initiate 15 its opening movement in case the door should be struck or jammed by lading piled against its inner face.

A further object is to provide a device of 20 this character by which the door may be fastened and sealed in a fully closed or partially open position, as may be desirable, for purpose of ventilation or the like.

A still further object is to provide means 25 for preventing the hasp from coming into contact with and breaking the seal.

Other objects and advantages of this invention should be readily appreciated as the same becomes better understood by reference to the following description when considered 30 in connection with the accompanying drawings.

Fig. 1 is a fragmentary side elevation of a car equipped with my invention;

Fig. 2 is a horizontal sectional view on the 35 line 2—2 of Fig. 1; and

Fig. 3 is a fragmentary side elevation of a car equipped with a modified form of this invention.

Fig. 4 is a section taken at the line 4—4 of 40 Fig. 3;

Fig. 5 is an enlarged section taken at the line 5—5 of Fig. 3.

Referring now to the drawings more in detail, reference character 4 designates a 45 stopping post or jamb against which a car door 5 is adapted to close. The door is preferably provided on its forward edge with a reinforcing bar 6 to protect this edge against 50 injury and is also provided with a horizon-

tal extending bar or plate 7 secured to the door by bolts 8.

A plate 9 provided with a horizontal groove 11 on its underside to accommodate the bar 7 and a vertical groove (not shown) also on its underside to accommodate the bar 6 is secured to the door 5 over said bars by bolts 12. This plate 9 is provided with an outwardly projecting hasp receiver or keeper 13 and a vertical extension 14 as best shown in Fig. 3. The hasp receiver 13 is provided on its upper face with a groove 15 adapted to receive the edge of a hasp 16 at the upper side of one of a pair of apertures 17 and 18 provided in said hasp and adapted to receive said receiver 13 therethrough. The apertures 17 and 18 are spaced longitudinally in the hasp 16, the latter being pivoted as will be hereinafter explained to the door jamb whereby the door may be fastened in closed position with the receiver 13 in the aperture 17 or in partially closed position with the receiver in the aperture 18.

The hasp 16 is provided with a handle portion 19 at one end and is pivotally attached 55 at its other end to a bolt 21 or other fastening means secured to the door jamb. In this case the bolt 21 extends through the door jamb. In this case the bolt 21 extends through the door post 4 and is secured by a nut on the inside. A plate 22 is secured on the outer surface of the door jamb at the base of the bolt 21 and a plate 36 is secured to the first plate and provided with a portion which is spaced outwardly therefrom the bolt 21 extending through said portion. The hasp 16 is carried on the bolt 21 between the plate 22 and the outwardly spaced portion of the plate 36. The inner side of the plate 36 is adapted 60 to engage the hasp 16 whenever the same commences to swing and thus maintains the latter in a vertical position and prevents swinging thereof in a longitudinal plane. By thus preventing swinging of the hasp 16 the danger of the same being caught between 65 the edge of the door and the jamb is prevented.

When the door is in fully closed position with the receiver 13 extending through the aperture 17 in the hasp or in partially closed 70

position with the receiver 13 extending through the aperture 18 in the hasp, a hasp retainer and seal protector in the form of an L shaped member 24 rotatively carried by a pin 25 mounted in the upper end of the extension 14 may be rotated from the dotted line position shown in Fig. 1 to the full line position to prevent lifting of the hasp sufficiently to disengage it from the groove of the receiver and to prevent it from coming into contact with and breaking the seal as will be hereinafter explained. The member 24 is enabled to prevent lifting of the hasp when in the operative position shown in Figs. 15 and 3 by means of an outwardly projecting portion 26 which upon a selected rotative position of said member extends over the hasp 16 above the receiver 13 to retain said hasp in the groove 15 of the receiver. When 20 in this position a vertical aperture 27 in the outer end of the portion 26 registers with a vertical aperture 28 in the receiver 13 exteriorly of the groove 15. The usual car seal 29 may then be threaded through the apertures 27 and 28 so that the member 24 cannot be rotated to permit removal of the hasp to thereby open the car without breaking said seal. It will be noted that when the hasp is in fastened position it overlies the 25 ends of a number of the bolts 12 so as to preclude their removal and the removal of the fastener without breaking the seal. The upper portion of the member 24 is made larger than the apertures 17 and 18 so that even 30 should the pin 25 be removed it would be impossible to draw said member through either one of said apertures and gain access to the car without breaking the seal.

The hasp 16 is designed not only to perform the function of fastening the car but to also perform the function of a door opening and door closing device thus doing away with the necessity of additional mechanism to accomplish this purpose. With this end 35 in view the hasp 16 is shaped on its upper edge with an offset convex cam surface 31 adapted to engage an outwardly projecting stud or knob 32 carried by the plate 9 near the forward edge of the door as shown in Fig. 1 for forcing the door open. The lower edge of the hasp 16 opposite the surface 31 is shaped to provide a concave cam surface 34 adapted to engage the knob 32 as shown in the dotted line position 35 in Fig. 1 for closing the door. The force exerted on the handle 19 of the hasp in the construction line position 33 in Fig. 1 to open the door will, of course, be exerted in a counter-clockwise direction and vice versa, the force exerted in the dotted line position 35 to close the door will be in a clockwise direction.

The hasp affords considerable leverage 40 which is highly desirable for opening and closing the door and this leverage is further

increased by the cam shape of the surfaces 31 and 34 which engage the projecting knob 32. By means of this mechanism the door may be forced into an open or closed position against considerable resistance.

In the modification a U-bolt 39 is used in place of the straight bolt 21 and the plate 36 is eliminated.

A retaining plate 38 is secured on the outer surface of the door jamb at the base of the bolt 21 and is provided with a hole or recess into which the short leg 37 of the U-bolt fits, so as to prevent rotation of the bolt and render it impossible for a pilferer to unscrew the bolt and release the door. The hole or recess for the short leg is so positioned on the plate 38 with respect to the base of the U-bolt that the latter is disposed on an angle so that when the hasp is cast off from the receiver or is otherwise released, it will slide down to the leg of the U-bolt to a position where it cannot be damaged by contact with the door should the door be suddenly closed.

While the accompanying drawings show the hasp as secured to the car body and the lock to the door it is obvious that these positions could be reversed.

I am aware that many changes could be made without departing from the principles of this invention and I therefore do not wish to be limited to the details shown or described.

I claim:

1. The combination with a pair of relatively movable parts such as a door and the jamb therefor, of a hasp pivotally mounted on one of said parts, a hasp receiver mounted on the other of said parts and adapted to be engaged by said hasp, a retainer movable on the second part to hold said hasp against disengagement from the receiver, and a stud projecting from the second part, said hasp and stud being shaped for temporary locking and camming engagement whereby said parts may be forced by means of said hasp toward and away from each other.

2. The combination with a pair of relatively movable parts such as a door and the jamb therefor, of a stud projecting outwardly from one of said parts, a hasp pivoted on the other of said parts and provided on its opposite edges with cam surfaces adapted for temporary locked engagement in camming relation with said stud, a hasp receiver mounted on the first part, and means for holding said hasp in locking engagement with said receiver.

3. The combination with a pair of relatively movable parts such as a door and the jamb therefor, of a stud projecting from one of said parts, a hasp pivoted on the other of said parts and shaped for temporary locking and camming engagement with said stud whereby said parts may be

forced by means of the hasp toward and away from each other, the locking engagement preventing accidental slippage of the hasp from the stud, and a hasp receiver mounted on the first part.

5 4. In a device of the character described, the combination of a keeper attached to a door, a hasp support anchored to the wall at the side of said door, a hasp pivotally connected at one end to said support and adapted to engage with said keeper, and means on said wall associated with said support for preventing the hasp from swinging longitudinally of the door in one direction regardless of the relative position of the door.

10 5. In a device of the character described, the combination of a keeper attached to a door, a hasp support anchored to the wall at the side of the door, a hasp pivotally connected at one end to said support and adapted for interlocking engagement with said keeper, a stud projecting laterally from said door adapted for temporary interlocking engagement with a portion of said hasp, said 15 portion of said hasp being adapted for temporary interlocking engagement with said stud and having curved cam surfaces on its upper and lower margins adapted to co-act with said stud when the hasp is operating 20 on said stud for closing and opening the door to exert a substantially horizontal thrust on said stud at all positions of co-action between the hasp and stud.

25 In witness of the foregoing I affix my
30 signature.

35 EARL F. JAGER.
